UNITED STATES PATENT OFFICE.

WILLIAM H. MULLINS, OF SALEM, OHIO.

DESIGN FOR A ROOFING-PLATE.

SPECIFICATION forming part of Design No. 24,082, dated March 5, 1895.

Application filed September 26, 1894. Serial No. 524,206. Term of patent 7 years.

To all whom it may concern:

Be it known that I, WILLIAM H. MULLINS, a citizen of the United States, residing at Salem, in the county of Columbiana and State of Ohio, have invented and produced a new and original Design for Roofing-Plates, of which the following is a description, reference being had to the accompanying drawing, in which the figure is a perspective view illustrating my design.

The general purpose of this design is the adornment of roofs for buildings, having as a primary object the production of a roofing-plate which is aesthetic in its appearance, and a suitable covering for buildings, gables, dormers, &c., in the better class of architectural structures.

With this object in view the essential features of my invention reside in the plate now to be particularly described, and consist in the features hereinafter pointed out.

Reference being had to the drawing and letters thereon which forms part of this specification, it will be observed that the plate constituting the subject-matter of this specification, presents substantially the outline of a rhomboid in shape, the numerals 1 and 2 re-

spectively representing alternating courses of ornamented and plain shield shaped bosses. Each of the said bosses 1 is provided with a 30 geometric antheunion ornament formed by alternating sunken and raised arises 3 and 4 converging to a common center, and terminating in a pear-shaped embossment 5; while both of the said bosses 2 are plain and unornamented except that their lower edges 6 are well rounded for the purpose of imparting to the boss a full and symmetrical appearance. In addition it will be noted that the ends 7, 7, of the roofing plate are cut or formed on an 40 angle approximating an oblique angle, while the lower edge 8 thereof conforms in outline to the lower edge of tiles 1, as shown.

Having thus described my invention, what I claim, and desire to secure by Letters Patent, is—

The design for an ornamental roofing-plate, substantially as herein shown and described.

In testimony whereof I subscribe my signature in presence of two witnesses.

WM. H. MULLINS.
